UNITED STATES PATENT OFFICE.

ROBERT JOY, OF OSWEGO, NEW YORK, ASSIGNOR TO THOMSON KINGSFORD,
OF SAME PLACE.

STEAM-BOILER.

SPECIFICATION forming part of Letters Patent No. 580,867, dated April 20, 1897.

Application filed March 5, 1896. Serial No. 581,874. (No model.)

To all whom it may concern:

Be it known that I, ROBERT JOY, of Oswego, in the county of Oswego, in the State of New York, have invented new and useful Improvements in Steam-Boilers, of which the following, taken in connection with the accompanying drawings, is a full, clear, and exact description.

This invention relates to the class of steam-boilers which are placed in an upright position and are provided with vertical flues passing through the water-spaces of the boiler and receiving the products of combustion through them.

15 The invention consists in an improved organization of an upright return-flue boiler which is simple in construction and possesses a maximum amount of heating-surfaces disposed in the most effective manner and permitting free circulation of the water to and from said heating-surfaces, and also possesses other advantages, as hereinafter described.

25 In the annexed drawings, Figure 1 is a front elevation of a steam-boiler embodying my invention. A portion of the boiler-shell is broken away to show the interior of the boiler. Fig. 2 is a central vertical section from the front to the rear of the boiler; and Figs. 3 and 4 are horizontal transverse sections, respectively, on lines X X and Y Y in Fig. 2.

30 Similar letters of reference indicate corresponding parts.

35 A denotes the boiler-shell, which is preferably of cylindrical shape and is placed in an upright position.

B represents the fire-box, which is located in the lower portion of the boiler-shell and has, preferably, its vertical walls extending below the grate C to form the ash-pit D.

40 Said fire-box I prefer to form also cylindrical and place the same eccentric to the boiler-shell, as more clearly shown in Figs. 3 and 4 of the drawings and for the purpose herein-after explained.

45 The fire-box is surrounded by a water-space a, the bottom of which is formed of a horizontal plate b, arranged nearly in the plane with the fire-grate and secured to the boiler-shell and fire-box shell. By means of 50 the plate b a smoke-flue e is formed in the base of the boiler-shell and around the ash-

pit D. In the upper part of the boiler-shell is arranged a combustion-chamber F, which is conical in shape and secured at its small end to the flange of an opening in the top plate 55 of the boiler-shell. Said end of the combustion-chamber is provided with a removable top plate G for the purpose of affording access to the fire-flues hereinafter described. In order to brace the sloping wall of the combustion-chamber so as to obviate the use of the expensive stay-bolts for said purpose and at the same time to enlarge the heating-surfaces of the said combustion-chamber and increase the efficiency thereof, I form the circumferential wall thereof corrugated from the top to the bottom, as shown at f. Said corrugated wall I prefer to form of sheet steel or iron and of vertical sections pressed into their corrugated shape by means of suitable dies in a hydraulic press, which sections are subsequently united by rivets or otherwise to form water-tight joints.

60 In order to protect the top plate G from excessive heat, I form the same of two metal sheets with asbestos or other non-heating material h packed between them and tied together by means of rivets i i. From the top of the fire-box B to the combustion-chamber F extend vertically the direct flues l l, and 65 from the bottom of the combustion-chamber to the smoke-flue e extend the return-flues l'.

70 By the eccentric arrangement of the fire-box in relation to the boiler-shell, as herein-before stated, I obtain an enlargement of the 75 water-space a around the rear portion of the fire-box, and in this enlarged portion of the water-space are arranged the series of return-flues l'.

75 To the rear portion of the boiler I attach 80 the smoke-chamber H, which communicates at its base with the smoke-flue e and has attached to it the exit-flue I.

85 The smoke-box H is formed with forwardly-diverging side walls, so as to cause said smoke-box to extend nearly half-way around the boiler-shell, to which they are attached, as shown in Fig. 3 of the drawings. In this manner nearly the entire rear portion of said shell is inclosed and made to serve as the front wall 90 of the smoke-box. Said portion of the boiler-shell is thus exposed to the heat of the prod-

ucts of combustion entering the smoke-box, and therefore the efficiency of the boiler is enhanced.

It will be observed that by the described arrangement of the return-flues *l* back of the fire-box and smoke-box *H* back of the said return-flues the products of combustion pass from the direct flues *l* rearward to the return-flues *l'* and thence down through the latter flues again rearward to the smoke-box *H*, from whence they escape through the exit-pipe *I*. Said successive rearward travel of the products of combustion facilitates the circulation of the same and at the same time thoroughly heats the return-flues and back portion of the boiler-shell, from which the heat is readily absorbed by the water, which is permitted a free circulation through the boiler.

What I claim as my invention is—

1. The herein-described steam-boiler, comprising the shell, the fire-box, located eccentrically within the lower portion of the shell, the smoke-box at the rear of the shell having forwardly-diverging sides attached to the sides thereof, the horizontal plate extending from the fire-box to the wall of the shell to form a smoke-chamber in the lower end of the

boiler, said smoke-chamber being in open communication with the smoke-box, a conical corrugated combustion-chamber above the fire-box and within the shell, fire-tubes leading from the top of the fire-box to said combustion-chamber, and return smoke-flues leading from said combustion-chamber to said smoke-chamber.

2. In a steam-boiler, the combination with the shell, of a fire-box in the lower portion thereof, a horizontal plate arranged to form a smoke-chamber in the lower part of the shell, a smoke-flue leading from said chamber, a conical corrugated combustion-chamber located within the shell and above the fire-box, the upper end of said combustion-chamber extending to the top of the shell, a removable cap closing said upper end, fire-tubes leading from the fire-box to the combustion-chamber, and return smoke-flues leading from the combustion-chamber to the smoke-chamber.

In testimony whereof I have hereunto signed my name this 3d day of February, 1896.

ROBERT JOY. [L. S.]
